GOBLET

Marvin G. Yutzey, Moundsville, W. Va., assignor to Fostoria Glass Company, Moundsville, W. Va., a corporation of West Virginia

Application December 28, 1949, Serial No. 6,884

Term of patent 14 years

(Cl. D36—8)

To all whom it may concern:

Be it known that I, Marvin G. Yutzey, a citizen of the United States of America, residing at Moundsville, in the county of Marshall, and State of West Virginia, have invented a new, original, and ornamental Design for a Goblet, of which the following is a specification, reference being had to the accompanying drawing, forming a part thereof, wherein:

Fig. 1 is a side elevational view of a goblet showing my new design;

Fig. 2, a horizontal sectional view taken on the line 2—2 of Fig. 1, looking in the direction indicated by the arrows; and,

Fig. 3, a horizontal sectional view taken on the line 3—3 of Fig. 1, looking in the direction of the arrows.

I claim:

The ornamental design for a goblet, as shown.

MARVIN G. YUTZEY.
